UNITED STATES PATENT OFFICE.

ANDREW J. HOPKINS, OF KAUFMAN, TEXAS.

COTTON-TRAMPER.

1,388,715.

Specification of Letters Patent. Patented Aug. 23, 1921.

Application filed October 8, 1919. Serial No. 329,249.

To all whom it may concern:

Be it known that I, ANDREW J. HOPKINS, a citizen of the United States, residing at Kaufman, in the county of Kaufman and State of Texas, have invented certain new and useful Improvements in a Cotton-Tramper, of which the following is a specification.

This invention relates to improvements in apparatus for tramping and packing cotton and more particularly to means for automatically feeding cotton to a tramper at predetermined intervals.

The primary object of the invention is to construct a feed mechanism which will be operated in conjunction with the apparatus for tramping cotton so that on the return stroke of the tramper a supply of cotton will be automatically delivered to the press chamber to be compressed by the power stroke.

Another object of the invention is to provide means in conjunction with the feed mechanism and tramper whereby upon completion of the return stroke of the tramper a new supply of cotton will be delivered to the feed mechanism from the condenser.

A further object of the invention is to provide a tramping and feeding mechanism wherein the successive operations may be regulated and be made to follow one another in the proper sequence and at the proper time intervals.

Other objects of this invention not at this time more particularly enumerated, will be clearly understood from the detailed description and drawings forming a part of this specification.

Furthermore this invention consists in the novel arrangement and combination of parts more particularly described in the following specification and embodied in the claims appended hereunto and forming part of this application.

Referring to the drawings:

Figure 1 is a front elevation of the invention.

Fig. 2 is a side elevation of a portion of the operating mechanism.

Fig. 3 is a side elevation of the invention as illustrated in Fig. 1.

Fig. 4 is a fragmentary view of the feed mechanism.

In the drawings like characters of reference indicate like or similar parts throughout the several views.

In broad terms my invention consists in several distinct but interactive elements, namely; the feed mechanism generally designated by the numeral 1 and illustrated in detail in Fig. 4 of the drawings; the operating mechanism generally designated by 2; and the tramping mechanism designated by 3. The invention as an entirety is used in conjunction with a condenser which is usually placed on the second floor of a gin-house and in close proximity with the press box which is usually located on the floor beneath. From the condenser a flue or other suitable conveying means (not shown) delivers the cotton bat to the feed mechanism 1, from which place the object of the present invention is to periodically deliver it to the tramping mechanism 2 for converting it into bales of suitable size.

Referring particularly to Figs. 1 and 2 of the drawings, the supporting frame work of the tramper is mounted on sills 4, and comprises a series of cross beams 5 of varying length; the exterior two of which extend somewhat beyond the others as at 6 to form supports for the bearings 7 of the power shaft 8. The two rearward extensions 9 of the cross beams likewise form supports for the bearings 10 of the upper and lower short shafts 11 and 12 respectively. Mounted on each of the sills 4 and converging upwardly to a point adjacent to each other are complementary pairs of uprights 13 connected at their upper extremities by transverse beams 14 upon which are mounted the bearings 15 of the shafts 16. The innermost pairs of the uprights 13 are secured each to and are braced from the sills 4 by the diagonal truss-rods 17.

The main power shaft 8 is provided with sprocket wheels 18 and tight and loose pulleys 19, the last named being designed for operative connection with a suitable source of energy (such as the power plant of the condenser). Chains 20 operatively connecting sprocket wheels 18 and 21, the last named carried by shafts 16, impart movement thereto which is carried therefrom to shaft 22 through the medium of the sprockets 23 and 24 connected by chains 25.

Keyed or otherwise suitably secured to the inner ends of the shaft 22 are sprocket wheels 26 connected by chains 27 to the idlers 28 carried upon the inner ends of the shafts 16. Carried by the chain 27 is a cross head

29 to which are connected at points adjacent the chain, the parallel connecting rods or plungers 30, the lower ends of which are movably secured in the bearing 32 of the trumper follower 31.

It will be seen from the foregoing description that upon rotation of the power shaft 8 that vertical reciprocation is imparted to the trumper follower 31 through the medium 10 of chains 27 as operated from sprockets 26, shaft 22.

Suitably secured upon one side of the trumper follower 31 and adapted to be reciprocated thereby is an apron or partition 33 having openings 34 formed therein to permit cotton to be fed to the press box at predetermined intervals, from the feed mechanism generally designated by the numeral 1. Upright grooved standards 35 15 suitably secured to the sills 4 serve the dual purpose of supporting the apron 33 and acting as a foundation for the feed mechanism generally designated by 1.

Referring now more particularly to Fig. 25 4 of the drawings, the feed mechanism in detail consists of the apron or partition 33 which as before stated is carried by the trumper follower 31 and reciprocates therewith in the grooved standards 35 mounted 30 on the sills 4. Suitably fixed on the lower ends of the standards 33 and slightly above the feed box are end pieces 36 to which is secured the sheet metal casing 37 which forms the outer side and bottom of the feed mechanism box. It has been found desirable to reinforce this casing by strips 38 as the vibration otherwise tends to displace it. Midway the extremities of the end pieces 36 are extensions 39 which support the bearings (not shown) of the shaft 40. A drum 41 having concave fingers 42 is mounted on the shaft within the casing 37 and upon rotation forces the cotton periodically through the openings 34 into the press box where it is compressed by the downward or power stroke of the trumper follower 31.

A sprocket 43 mounted on the power shaft 8 is operatively connected with a sprocket 50 44 on the shaft 40 by the chain 45, and it has been found expedient to support the chain intermediate the sprockets by idler pulleys 46 mounted on shafts 11 and 12 before referred to.

55 Each operative element of the present invention is actuated from the power shaft 8, thus eliminating to a great extent unnecessary parts which would tend to decrease the efficiency of the machine.

60 Upon the rear surface of the apron or partition 33 are mounted at 47 a pair of spaced supports 48 upon which is movably carried the cover 49 of the casing 37. I have found it expedient to secure the cover 65 to the supports by means of straps 50 but

other securing means may be found desirable when the device is placed upon a commercial basis.

It will be seen that upon extreme upward movement of the apron 33 the cover 49 is 70 raised allowing ingress of cotton to the feed mechanism from the condenser. Upon downward movement of the apron (or power stroke) the cover is dropped so that no more cotton will be fed to the press box. 75 To properly position the cover and limit its downward movement I have devised a pair of brackets 51 carried by the standards 35 and having fingers 52 which contact with extensions 53 on the cover at the proper time 80 to position it upon the casing 37. The sloping portion of the brackets also serve as guides for the cover upon upward movement thereof.

Assuming that the apparatus has been 85 installed in a gin-house equipped with gins, condenser and press, and the gins started in the operation of ginning cotton; the operation of this invention would be as follows:

Upon the upward stroke of the trumper 90 follower 31 the cover 49 is raised so that cotton is delivered from the condenser to the feed mechanism where it is quickly passed into the press box through the apron. Upon commencement of the power stroke 95 the cover is released and drops to its closing position upon the casing and the openings 34 having passed the lowermost edge of the casing are closed to further ingress of cotton to the press box. 100

In order to allow the air trapped by the trumper follower on its power stroke to escape I have provided an outlet pipe 54 extending upwardly from the central portion of the trumper follower. 105

Attention is directed to the fact that at the termination of the return stroke of the trumper follower free movement of cotton from the feed mechanism directly to the press box is permitted and that as the power 110 stroke progresses access to the press box is constricted until all the openings have passed below the upper edge of the press box.

Such changes in the construction of my improved apparatus as are permissible by 115 the appended claims, may be resorted to without departing from the spirit and scope of the invention.

What I claim is:

1. A device for tramping cotton comprising a tramping member and a feed member, a closure carried by said tramping member for regulating the amount of cotton transmitted by the feed member to the tramping member and means carried by said closure 125 for regulating the amount of cotton transmitted to the feed member.

2. A device for tramping cotton comprising a tramping member and a feed member, a closure carried by said tramping member 130

for regulating the amount of cotton transmitted by the feed member to the tramping member, and a cover carried by the said closure for limiting the amount of cotton delivered to the feed member.

3. A device for tramping cotton comprising a vertically reciprocating tramping member and a feed member coöperative therewith, a partition carried by said tramping member for regulating the action of the feed member with respect thereto, a movable cover carried by the partition for periodically admitting quantities of cotton to the feed member, and means for simultaneously operating the tramping and feed members.

4. A device for tramping cotton comprising a tramping member and a feed member, means on said tramping member for regulating the action of the feed member with respect thereto, a drum in the feed member for transferring cotton from the feed member to the tramping member, and a cover movably mounted on said first named means for periodically allowing cotton to be delivered to the feed member.

5. A device for tramping cotton comprising a tramping member and a feed member,

a partition having openings therein carried by said tramping member for regulating the quantity of cotton delivered by the feed member to the tramping member, a movable cover carried by the partition for limiting the amount of cotton delivered to the feed member, means for limiting the movement of the cover with respect to the feed member and means for simultaneously actuating said feed member and tramping member.

6. The combination in a device for tramping cotton comprising a frame, and a tramping member carried thereby, of a feed member supported adjacent said tramping member, a partition carried by the tramping member and slidably attached to said frame for limiting the amount of cotton delivered from the feed member to the tramping member, and a cover carried by the partition and vertically movable with respect to the frame for limiting the amount of cotton delivered to the feed member.

In testimony whereof I affix my signature hereto.

ANDREW J. HOPKINS.
